DESIGN FOR A JAR

Ivor Cordy, Washington, Pa., assignor to Hazel-
Atlas Glass Company, Wheeling, W. Va., a cor-
poration of West Virginia

Application September 16, 1937, Serial No. 71,651

Term of patent 14 years

To all whom it may concern:

Be it known that I, Ivor Cordy, a citizen of the United States, residing at Washington, in the county of Washington and State of Pennsylvania, have invented a new, original, and ornamental Design for a Jar, of which the following is a specification, reference being had to the accompanying drawing, forming part thereof.

Figure 1 is an elevational view of the jar showing my new design; and

Figure 2 is a similar view of the jar turned through 90°.

In the specific embodiment of the invention illustrated, the side opposite to that shown in Figure 2 is substantially the same, and the side opposite to that shown in Figure 1 is substantially the same, except that the panel is not stippled or frosted.

I claim:

The ornamental design for a jar, as shown and described.

IVOR CORDY.
